F. P. Grier

Attorney,

UNITED STATES PATENT OFFICE.

PHILIP NEARY, OF SEATTLE, WASHINGTON.

EXCAVATING DEVICE.

Application filed May 17, 1922. Serial No. 561,568.

To all whom it may concern:

Be it known that PHILIP NEARY, citizen of the United States of America, residing at Seattle, in the county of King and State 5 of Washington, has invented certain new and useful Improvements in Excavating Devices, of which the following is a specification.

This invention relates to an improvement 10 in excavating means of that type embodying a power operated shovel-like excavator, adapted to force or cut its way into the material to be excavated, and to receive a load from such operation for transportation and 15 dumping at a remote point.

In excavators of this type, considerable difficulty has been experienced in properly loading the excavator by forcing or drawing the same into the material, as thru the 20 shovel-like type of the usual excavator, any obstruction in the path thereof tends to tilt or deflect the excavator, with a consequent reduction in the quantity of material picked up.

25 The present invention aims to overcome this particular objection, among others, by constructing the excavator proper of cylindrical form, and mounting it for free rotative movement in the supporting frame, 30 whereby in the event of an obstruction in the path of the excavator, a simple rotative movement of the excavator results without in any way interfering with a proper digging and cutting movement of the excavator. Therefore, a full digging load is 35 assured under all circumstances.

In excavators of the usual type, it is customary to provide a door or closure capable of being released from a remote point when 40 it is desired to dump the load of the excavator. Heretofore, the door locking means has formed a part of the excavator proper, and as such accumulated dirt in the use of the excavator, and required frequent cleaning for satisfactory service.

A further object of the invention is the provision of door locking or holding means arranged remote from the excavator proper and as such ordinarily free of dirt accumulation, hence insuring a proper release and

locking of the door under all working circumstances.

The invention is illustrated in the accompanying drawings, in which:

Fig. 1 is a perspective view of the improved excavator. 55

Fig. 2 is a front elevation of the excavating receptacle.

Fig. 3 is a detail, showing particularly 60 the door controlling means.

Fig. 4 is a transverse section thru the excavating receptacle, showing particularly the details of construction.

Fig. 5 is a transverse section thru the excavating receptacle, showing the means for 65 rotatably supporting the same.

The improved excavator is of the type designed more particularly for slidable support on a cable-like member, indicated at 70 1, the excavator being drawn along this member to accomplish the excavating work.

The excavating receptacle comprises a cylindrical shell 2, open at both ends and exteriorly reinforced by longitudinally arranged narrow strips 3 having outturned 75 edge flanges 4. The strips extend from the forward edge of the shell to a point short of the rear edge thereof, and are bolted or otherwise secured at 5 to the shell. In applied position, the reinforcing strips have 80 their edge flanges 4 spaced apart, and strengthening bars or ribs 6 are secured between adjacent edge flanges by bolts or rivets 7.

The projection of the shell beyond the 85 rear end of the reinforcing strips provides an annular channel 8, the strips being interrupted slightly in rear of the forward end of the shell to provide a second similar 90 annular channel 9. The ribs 6 are omitted 95 between the edge flanges 4 of the reinforcing strips and digging teeth 10 of an appropriate form are removably secured between the edge flanges 4 of the reinforcing strips at this forward portion of the reinforced excavating receptacle. The digging teeth 10 are of usual digging point form, and rearwardly of the point are recessed to receive the forward edge of the shell. These teeth on the outer side of the shell have 100

rearwardly extending portions which are inserted between the flanges 4 of each pair and secured thereto.

As thus arranged, the receptacle is of cylindrical form, presenting exteriorly a series of longitudinally arranged ribs, which reinforce the receptacle and at the same time provide against excessive wear of the body thereof, the forward circular edge 10 of the receptacle being provided throughout with a series of spaced cutting or digging teeth.

The receptacle as a whole is supported in a frame including longitudinal frame bars 11, 12, and 13, the bars 11 and 12 being diametrically opposed with respect to the receptacle, and the bar 13 being centrally above the receptacle. Annular hangers 14, secured to the respective bars 11, 12, and 13, seat in annular channels 8 and 9 of the receptacle, to thereby rotatively support the receptacle in the frame.

An upstanding frame work indicated generally at 15 is connected to the longitudinal frame bar 13 and braced at 16 from the side frame bars 11 and 12. Upper and lower guide rollers 17 are mounted in the frame 15 at appropriate points, the rollers being grooved to cooperate with the cable 1, whereby the excavator as a whole is adapted for appropriate movement longitudinally of the cable. The inclined frame bars 27 forming part of the frame 15, are inclined upwardly and forwardly and are connected at their upper ends above the upper guide rollers 17 by longitudinal bars 28. These bars extend rearwardly of the rearmost bars 27 and are connected to the upper end of rods 29, which at their lower ends are connected to a curved frame 30, the forward end of which is connected to the bars 13, and the rear end of which is provided with a roller 31 to cooperate with the arm 20 of the door.

The rear end of the excavating receptacle is closed by a door 18 pivotally supported at 19 at the rear end of the longitudinal frame bar 13, an arm 20 rising from the pivotal connection as a rigid part of the door structure. The door is adapted to be closed by gravitational movement, and to be held closed by a series of interconnected levers 21, which extend thru and terminate in advance of the receptacle in a trip lever 22, pivoted between the forward bars 27 and provided with a weight 23 adapted for adjustable positioning on the trip lever. The free end of the rearmost lever 21 which is pivotally supported between the rear bars 27 is adapted to rest normally immediately in advance of the arm 20, thus preventing opening of the door, the system of levers being adapted for adjustable connection one to the other, through a link 24 adapted for connection with any one of a series of holes in each of the levers. When the trip lever is moved

upwardly, the lever 21 is moved from in front of the arm 20 and the door 18 is free to open under the influence of the contained load to discharge the same. A trip 25 is arranged for adjustable connection with the cable 1, and is of a form to permit the free end of the trip lever to ride therein, so that further forward movement of the receptacle will operate the series of levers to release the door. The door operating means, as well as the means for holding the door in closed position, are thus arranged wholly beyond the excavating receptacle, and are little liable to become inoperative thru the accumulation of dirt.

The side frame bars 11 and 12 are formed at their forward ends for the removable connection thereto of a draft means 26, here shown as a chain, thru which the excavator may be forced into the material to be excavated or drawn from place to place after being loaded.

As stated, the excavating receptacle is mounted for free rotation in the hangers 14, and as the receptacle is of cylindrical form, it is of course apparent that it would be effective for loading purposes in any rotative position. Therefore, if obstruction is encountered in digging, the natural tendency to deflect the edge of the receptacle, which in the usual shovel type would prevent proper loading, will, in the present type, merely turn the receptacle in its bearings until the obstruction is displaced or the receptacle rides around the same. In any event, a normal load will be obtained under all conditions of operation.

Claims:

1. An excavating receptacle comprising a shell of cylindrical form, longitudinally arranged reinforcing strips secured on the exterior of the shell and having out turned flanges and reinforcing bars secured between said flanges.

2. An excavating receptacle comprising a cylindrical shell, spaced strips having out turned edge flanges secured to the exterior of the shell adjacent one end thereof, and digging teeth removably secured between said flanges.

3. An excavator including a frame, annular hangers carried thereby, and a cylindrical excavating receptacle mounted for free rotative movement in the hangers.

4. An excavator including a freely rotative excavating receptacle, a door closing one end thereof, and means arranged wholly beyond the receptacle for holding the door in closed relation, said means being operable to release the door for opening under gravitational influence.

5. In an excavator, a frame work, a receptacle revoluble therein and having a cutting edge, a door for the receptacle, a cable upon which the frame work is mounted for

sliding movement, and means arranged beyond the receptacle for tripping the door.

6. In an excavator, a frame work, a receptacle revoluble therein and having a cutting edge, a door for the receptacle, a cable upon which the frame work is mounted for sliding movement, and tripping means adjustably secured upon the cable, lever mech-

anism on the receptacle cooperating with the door and adapted to be engaged by the tripping means for automatically releasing the door in the travel of the frame work on the cable. 10

In testimony whereof I affix my signature.

PHILIP NEARY.
